UNITED STATES PATENT OFFICE.

WILLIAM L. BURKS, OF BELLEPOINT, WEST VIRGINIA.

TRAVERSING HOIST.

Application filed August 17, 1923. Serial No. 657,921.

This invention relates to traversing hoists, and more particularly to such a hoist in which a carriage travels along a suspended track or cableway under the control of machinery at one end thereof.

The invention has for its object the production of a novel system of cable control for the carriage of a traversing hoist. Another object is the provision of means for automatically controlling the movements of the carriage so that the danger of accidents due to the breaking of cables or lines is reduced to a minimum. Another object is the provision of a slack line in a traversing hoist system, which is employed to release the load holding mechanism and at the same time take up slack in the skidding line, so that a dropping of the load is assured.

In traversing hoists in general use the load is held suspended by a pulling back of the outhaul line. One of the objects of my invention is to overcome this necessity for holding back upon the outhaul line. This results in a reduction of power expended and a substantial saving in operating costs of the hoist.

Other objects and advantages of the invention will hereinafter appear in the following description and the novel features thereof will be particularly pointed out in the appended claims.

Like reference characters indicate like parts through the several figures of the drawings, in which—

Figure 1 is an elevation of a hoisting system employing the features of my invention;

Figure 2 is an elevation of the carrier with one of the housing plates removed for the purpose of showing the inclosed parts; and

Figure 3 is a cross sectional view through my carriage.

My invention is illustrated in the accompanying drawing, but it will be understood that it may be embodied in other forms than that shown without departing from the spirit thereof. The form illustrated and described is to be taken as indicative only.

The invention comprises a system of cables for supporting a travelling carriage and for controlling the movements of said carriage upon its track or cableway. It embodies a novel form of carriage, load holding mechanism and automatically operating brake. These parts will now be described in detail and their individual functions pointed out, after which a recital of their conjoint use will be given.

Referring to Figure 1 the numeral 10 represents a conventional skidding machine for hoisting apparatus of this type and it comprises an engine and three drums designed for control of the movements of the carriage 11. The drum 12 controls the skidding cable 13, the drum 14 controls the outhaul cable 15, while the drum 16 controls the slack cable 17. 18 represents the rig at the skidding end of the system while 19 represents the outhaul rig. Between the rigs 18 and 19 there is suspended a track or cableway 20. At the point 21 the skidding and slack cables are joined together. These cables move together, although, as herein-after explained, they have a limited movement with respect to each other.

The several control cables pass over suitable sheaves attached to the rigging and inclosed in the carriage. It will be appreciated that when the skidding and slack cables are wound upon their drums and the outhaul cable allowed to play off its drum, the carriage will be moved toward the skidding rig. This is usually when it is loaded. It will also be appreciated that when the outhaul cable is wound upon its drum and the skidding and slack cables permitted to play off their drums, the carriage will be advanced toward the rig 19.

The carriage 11 comprises a housing of two side plates 22, 22^a, joined together by bolts. These bolts carry spacing sleeves or bearing members, upon which the several sheaves inclosed in the housing revolve. The numerals 23, 23^a, indicate the supporting wheels for the carriage; these travel upon the cable 20. The sheave 24 is designed to support the skidding cable while the two

pairs of sheaves 25, 25, 26, 26, constitute guides for the loaded end of the skidding cable, which is in the form of a chain 27 having a stop block 28 at its end, from which block the hook 29 is suspended. The slack cable passes over the stationary sheave 30^a and over a sheave 30 formed as a part of the load holding device to be hereinafter explained.

10 Within the carriage housing 21 is mounted a brake 31, comprising jaws 32 and 33, the jaw 33 being formed as a part of the brake lever 34, which is pivoted in the housing upon the pin 35. The jaw 33 is so formed that its rear end is upon an increasing radius so that upon a downward movement of the free end of the lever 34, this jaw will grip the cable 20 with an increasing pressure.

15 20 Upon each side of the lever 34 there is formed a bearing lug 36 through which the pin 35 is eccentrically passed. Upon these bearing lugs 36 are mounted connectors 37 extending to the smaller jaw 32 and connected thereto by means of the pin 38. This small jaw is pivoted upon the bolt 39, and its gripping face is upon an increasing radius from the pin 39 rearwardly, so that upon a downward movement of the connectors 37, this jaw will be brought into increased gripping friction with the cable 20.

25 30 35 In order to normally exert a braking effect upon the carriage, I have provided an elastic tension device connected to the brake lever 31 at 40. This elastic tension device comprises a rod 41 extending through plates 42 and 43 and having the nut 44. On a pin 45 there is mounted a yoke 46, to which are 40 pivoted the rods 47, 47, which also pass through the plates 42 and 43. A coil spring 48 lies between the plates 42 and 43 and tends to spread the plates apart. This spring device exerts a continuous pull upon the lever 31 tending to apply the brake.

45 50 55 It will be appreciated that the spring device just described will apply the brake to the cable 20 by exerting a downward pull upon the free end of the lever 34, which will bring the jaws 32 and 33 in gripping relation with the cable. But I have provided means for overcoming the normal tendency to apply the brake by providing the lever 31 with the curved free end 34, to which I have attached the end of the outhaul line, as shown at 49. This outhaul line is used primarily to produce travel of the carriage from the skidding rig to the outhaul rig, and the normal pull upon the outhaul line in performing this function will be sufficient to lift the free end of the lever 31 and place the spring device under tension. It will be appreciated too that when the carriage is travelling in the opposite direction, the placing of the outhaul line under a slight ten-

sion will be sufficient to counteract the tension of the spring device and relieve the brake. In fact the usual sag in the outhaul line is generally sufficient to overcome the spring action. If however for any reason 70 the outhaul line should break, the brake will be automatically applied, and this will be true whether the outhaul rig is higher or lower than the skidding rig. If the carriage is travelling toward the outhaul rig there 75 would be a tendency to release the brake by the traverse of the cable through it. The tension of the spring device however is sufficient to exert a substantial braking effect.

80 In order to provide a means for releasing the load under various conditions of use of the carriage, I have provided within the carriage housing a load holding device comprising a pair of gripping elements 50 and 51 pivoted upon the bolts 52 and 53. Each 85 gripping element is formed of two straps between the outer ends of which is mounted a roller, shown in dotted lines in Figure 2 at 54. These rollers engage the under face of a chain link carried by the end of the 90 skidding line. The link 58 connects the gripping element 51 to the bolt 59 of an elastic tension device. Between the straps of the gripping element 51 the sheave 30 is mounted, over which the slack cable runs. 95 Between the straps of the gripping element 50 is pivoted the toggle link 55 connecting with the toggle lever 56 pivoted at 57 to the housing of the carriage. The opposite end of the toggle lever 56 is connected 100 to the bolt 59 of the elastic tension device.

105 This elastic tension device is similar to the one described in connection with the brake and tends to keep the gripping elements in contact with the chain link. It comprises the central rod or bolt 59 screwed through cap 60 and movable through the plate 61. There is a coil spring between the cap and plate tending to separate them. The end of this elastic tension device is mounted upon an extension 62 of the carriage housing, which extension is provided with an aperture through which the end of the rod 59 freely moves.

110 It will be understood that when the chain 27 is in its lowered position for loading, a pull upon the skidding line 13 will cause it to be brought up into the carriage until the block 28 rests between the faces of the sheaves 26, 26, when the gripping elements 50, 51, will engage the sides of one chain link 120 and the rollers 54, 54, the lower end of the link above. While the tension device will tend to hold the parts in this position, it is the angular position of the gripping elements and the weight of the load which accomplishes this result. In order to release the gripping elements, it is only necessary to exert a pull or jerk upon either end of the slack line while the other end is being held. Such a pull or jerk will cause the sheave 30 130

to be lifted and with it the gripping elements 50 and 51. The skidding line will then drop from the carriage under the weight of the load or of the chain 27, the slack thereof being taken up by the slack line.

It will be appreciated that the slack line is attached to the skidding line at a point sufficiently distant from the carriage to permit the chain end of the skidding line to reach the ground before the knot 21 reaches the carriage. Should it be desirable to release the load for any reason, a pull upon the slack line will not only cause the gripping elements 50 and 51 to be lifted and the chain end released but will also take the slack up in the skidding line, which is very desirable. Otherwise the weight of the slack in the skidding line might overbalance the weight of the chain end and prevent the successful operation of the hoist.

From the foregoing description, the construction and function of the individual parts of my invention will be clear. There remains to be set forth the action of these parts conjointly.

In Figure 1 I have shown the skidding machine lower than the outhaul rig. In this position of the parts the movement of the carriage toward the skidding machine is under the control of the outhaul line. If this line were to break and there was nothing to prevent it, the carriage would run down the supporting track or cableway and wreck the skidding rig. With my invention, upon a breaking of the outhaul line the brake elements 32 and 33 are applied and bring the carriage to a stop. This result is produced by the spring device when relieved of the tension upon the outhaul line in normal operation, it being understood that this spring device is strong enough to move the broken line.

Suppose now that the other cables would break, the carriage would be under the control of the outhaul line and no movement of the carriage could take place unless it were under control.

Suppose now that the outhaul rig is lower than the skidding machine, it will be seen that the brake 31 is not available to prevent the carriage from running into the outhaul rig. In this case there would be no danger of the outhaul line breaking after the load is suspended, but the skidding line would have the heavy strain and might break, when the outhaul rig would be wrecked. However, if it broke between the carriage and the joint 21, the weight would be immediately transferred to the slack line, when the gripping elements would be jerked open and the load allowed to drop.

If the skidding line should break at any other point, the carriage would move toward the outhaul rig until the joint 21 came into contact with the carriage, when again the

slack line would jerk the gripping elements apart, thereby dropping the load and stopping the carriage.

Having described my invention, what I claim as new and desire to secure by Letters Patent is:

1. In a traversing hoist comprising a suspended track or cableway and a travelling carriage having a load locking mechanism thereon, comprising a pair of interconnected gripping jaws, one of which carries a sheave, an outhaul line for securing movement of the carriage in an outhaul direction, means carried by the carriage for locking the same to the cableway upon a breaking of the outhaul line, a load lifting and skidding line for moving the carriage in the inhaul direction, a second cable secured to the inhaul line and passing over the sheave on the locking jaw for normally releasing the locking mechanism and for taking up slack in the inhaul line, and for automatically releasing the load upon a breaking of the inhaul line.

2. In a traversing hoist comprising a suspended track or cableway and a travelling carriage embodying a load holding mechanism and an automatic brake, an outhaul line for securing movement of the carriage in an outhaul direction and for maintaining said brake inactive, and a cable control for the movement of the carriage in the opposite direction comprising a combined load lifting and skidding line and a slack line associated therewith for releasing the load holding mechanism and for taking up the sag in said lifting and skidding line.

3. In a traversing hoist comprising a suspended track or cableway and a travelling carriage, a brake carried by said carriage and spring pressed toward braking position, an outhaul line for imparting movement to the carriage in the outhaul direction and for normally maintaining said brake inactive, a load holding mechanism within said carriage comprising an inclined gripping element, a combined lifting and skidding cable, the end of which is adapted to be engaged by said gripping element, and a slack cable connected to said skidding cable and to said gripping element and operable to take up the slack in said skidding cable and to release said gripping element.

4. In a traversing hoist comprising a suspended track or cableway and a travelling carriage, a skidding cable movable through said carriage to lift the load, mechanism upon said carriage for locking said load in lifted position, and means for automatically releasing the load locking mechanism upon a breaking of said skidding cable.

5. In a traversing hoist comprising a suspended track or cableway and a travelling carriage, a skidding line for lifting a load to said carriage and for moving the car-

riage upon said track or cableway, mechanism upon said carriage for holding the end of said line in lifted position, a slack line attached at one end to said skidding line and operable to release said holding mechanism upon a breaking of said skidding cable.

6. The combination of claim 4 in which

the locking mechanism comprises a jaw engaging the lifting cable and the releasing means comprises a cable attached to the skidding cable and operating to lift the locking jaw in either the normal or the automatic release of the load. 10

In testimony whereof I affix my signature.

WILLIAM L. BURKS.
